[57] CLAIM

The ornamental design for the chuck body, as shown and described.

DESCRIPTION

FIG. 1 is a isometric view of the chuck body looking down towards the top end showing my new design.

FIG. 2 is a side view revealing the surface relief of approximately one-half the chuck body.

FIG. 3 is a side view revealing the surface relief of approximately one-half the chuck body as would appear by rotation of the body through about 90 degrees about its longitudinal centerline from the position of FIG. 2.

FIG. 4 is a top view of the chuck body.

FIG. 5 is a bottom view of the chuck body showing the interior of the cup portion.

FIG. 6 is a sectional view revealing the interior surface relief taken along the lines 6—6 of FIG. 5.
